CLAIM

The ornamental design for a pipe gland, as shown and described.

DESCRIPTION

FIG. 1 is a perspective illustration of a portion of a pipe gland according to an embodiment of the present invention;

FIG. 2 is a front elevation illustration of the portion of the pipe gland shown in FIG. 1;

FIG. 3 is a section view of the portion of the pipe gland shown in FIG. 1, taken along section lines 3—3;

FIG. 4 is a top illustration of the portion of the pipe gland shown in FIG. 1; and,

FIG. 5 is a rear illustration of the portion of the pipe gland shown in FIG. 1.

The broken lines shown herein are for illustrative purposes only and form no part of the claimed design.
